UNITED STATES PATENT OFFICE

2,444,957

FLASH REDUCER

Leslie A. Skinner, Berkeley, Calif., assignor to
United States of America as represented by the
Secretary of War

Application September 27, 1944, Serial No. 556,051

5 Claims. (Cl. 102—49)

(Granted under the act of March 3, 1883, as
amended April 30, 1928; 370 O. G. 757)

1

The invention described herein may be manufactured and used by or for the Government for governmental purposes without the payment to me of any royalty thereon.

This invention relates to a flash reducer for reduction of the propellant flash of rocket propelled projectiles.

One of the major drawbacks to firing rocket propelled projectiles, particularly from shoulder launchers, has been the resulting high intensity flash of high temperature gases and burning powder from the nozzle of the projectile, particularly that occurring after the emergence of such projectile from the rocket launcher. It is obvious that such a flash is highly distracting to the firer and very revealing as to the location of the launcher.

Accordingly, it is an object of this invention to provide means to accomplish a substantial reduction of the flash of rocket propelled projectiles.

A particular object of this invention is to provide an improved mounting arrangement for a container of flash-reducing material within the low pressure region of the combustion chamber of the rocket projectile.

The specific nature of the invention as well as other objects and advantages thereof will clearly appear from a description of a preferred embodiment as shown in the accompanying drawing in which:

Fig. 1 is a longitudinal-sectional view of the rear portion of a rocket motor embodying the invention, showing a container of flash-reducing material mounted in such motor.

Fig. 2 is an enlarged elevational view shown partly in section, of one form of a container for a flash-reducing agent.

Fig. 3 is an enlarged elevational view partly in section of a modified form of a container for a flash-reducing agent.

There is shown in Fig. 1 in assembled relation a rocket projectile embodying this invention. The rocket projectile comprises a cylindrical housing 1 defining a combustion chamber 2. The rear end of housing 1 is shaped to define a constricted discharge passage 3 similar to a Venturi nozzle. A plurality of pivoted guiding fins 4 are preferably provided at the rear end of housing 1, being pivotally secured to an annular mounting flange 5 which is in turn suitably secured to housing 1. A tubular element 10 is provided extending through combustion chamber 2 concentrically therewith and terminating forwardly of discharge passage 3. While not limited thereto,

2

tubular member 10 preferably comprises a bursting tube which communicates with the head of the rocket projectile and contains a high explosive sufficient to shatter tube 10 and housing 1 upon impact with the target.

A propellant charge 11 is mounted within combustion chamber 2 and preferably comprises a plurality of long cylindrical powder sticks 12 lying around tubular member 10. Powder sticks 10 12 are retained within combustion chamber 2 by suitable trap wires 13.

In accordance with this invention, a container 20 is secured to the extreme rear end of tubular member 10. The container projects rearwardly 15 towards discharge passage 3 but does not extend into such passage. The location of the container is particularly important as will be brought out later.

Container 20 is preferably provided with thin flexible wall sections 21. As shown in Fig. 2 wall sections 21 may be shaped to produce a Sylphon-like construction. In the modification shown in Fig. 2, the container 20 is secured to tubular member 10 by means of a plug 15 having a threaded shank 16 threadably engaging a suitable hole in tubular member 10 and an enlarged head portion 17 around which end of walls 21 of container 20 are bent and held in sealing relationship against the end of tubular member 10.

An alternative construction of the container is disclosed in Fig. 3 wherein the container comprises a thin-walled cup-shaped member 22. The opened end of container 22 snugly surrounds the end of tubular member 10 and is sealed thereto by any suitable means, as for example, by welding.

The container is filled with a suitable flash-reducing agent preferably a liquid composition known as xylene. Xylene is known chemically as any one of the isomeric, colorless hydrocarbons, $C_6H_4(CH_3)_2$, derivatives of benzene. Such substance, when introduced in the form of a spray into gases produced by combustion of powder grains 12 effectively reduces the flash of such gases without reducing the efficiency of the gas blast inasmuch as xylene is itself combustible and produces additional gases which compensate for a reduction in temperature of the primary gases affected by the xylene. Irrespective of whatever type of container is utilized, a small opening 25 is produced in the end wall of container 20 adjacent the discharge passage 3 of the combustion chamber 2. The flash-reducing agent 24 may be conveniently loaded into the

container through the hole 25. A sealing plug 26 is then inserted in the hole 25. Sealing plug 26 is of the blow-out type which will provide an effective seal for the flash-reducing agent 24 so long as the pressure conditions inside and outside of the container are substantially equal. When the container 20 is positioned in a rocket projectile as described, i. e., in front of the discharge passage 3, the entire container will be located within a relatively low pressure region of the combustion chamber thus insuring that the thin-walled container will not be collapsed by the pressure developed within the combustion chamber.

Accordingly, during combustion of powder charge 11, the sealing plug 26 will be blown out of the container 20 by the relatively high exterior pressure produced and operating on the thin walls of the container and thereafter the flash-reducing agent 24 is forced out through opening 25 in container 20 into the gas discharge. The small size of opening 25 insures that flash-reducing agent 24 will be supplied gradually to the discharge gases, practically in the form of a spray, and thereby be effective for the entire burning time of the propellant.

It should be noted also that the forces produced by the initial rapid acceleration of the rocket projectile produce an inertia force of flash-reducing agent 24 upon sealing plug 26 tending to break out such plug. From the foregoing description, it is apparent that a simple and effective means for reduction of visible flash emerging from the nozzle of the rocket projectile is hereby provided.

I claim:

1. In a rocket projectile having a combustion chamber and a constricted discharge passage communicating with said chamber, the improvement comprising a thin walled container secured in said chamber forwardly of said discharge passage, said container being filled with a flash-reducing agent, said container having an opening adjacent said discharge passage and a blow-out sealing member secured in said opening whereby pressure developed within said combustion chamber will blow out said sealing member and disperse said flash-reducing agent thru said opening.

2. In a rocket projectile having a combustion chamber and a constricted discharge passage communicating with said chamber, the improvement comprising a flexible wall, Sylphon type container secured in said chamber forwardly of said discharge passage, said container being filled with a flash reducing agent, said container having an opening adjacent said discharge passage and a blow-out sealing member secured in said opening whereby pressure developed within said combustion chamber will blow out said sealing member and disperse said flash-reducing agent thru said opening.

3. In a rocket projectile having a combustion

chamber and a constricted discharge passage communicating with said chamber, a propellant charge in said chamber and a burster tube extending thru the chamber and terminating forwardly of the discharge passage, the improvement comprising a thin walled container secured to the rear end of the burster tube, said container having a portion projecting rearwardly toward said discharge passage but terminating forwardly thereof, said container being filled with a flash-reducing agent, said container having an opening adjacent said discharge passage and a blow-out sealing member secured in said opening whereby pressure developed within said combustion chamber will blow out said sealing member and disperse said flash-reducing agent thru said opening.

4. In a rocket projectile having a combustion chamber and a constricted discharge passage communicating with said chamber, a propellant charge in said chamber and a burster tube extending thru the chamber and terminating forwardly of the discharge passage, the improvement comprising a thin walled cup-shaped container constructed to surround the rear end of said burster tube and secured thereto, thereby defining an enclosed space between the rear end of said burster tube and the interior walls of said container, the base of said container being disposed forwardly of said discharge passage, said enclosed space being filled with a flash-reducing agent, said container having a central opening in its base and a blow-out sealing member secured in said opening whereby pressure developed within said combustion chamber will blow out said sealing member and disperse said flash-reducing agent thru said opening.

5. In a rocket projectile having a combustion chamber and a discharge passage communicating with said chamber, the improvement comprising a container secured in said chamber forwardly of said discharge passage, said container being filled with a flash-reducing agent, said container having an opening adjacent said discharge passage and means normally sealing said opening, said sealing means being removable upon development of pressure within said combustion chamber to allow said flash-reducing agent to disperse through said opening.
